UNITED STATES PATENT OFFICE.

HARRY M. NEWKIRK AND HENRY A. SCHMIDT, OF NEWPORT NEWS,
VIRGINIA.

CRANK CONNECTION FOR STEAM-ENGINES.

SPECIFICATION forming part of Letters Patent No. 614,745, dated November 22, 1898.

Application filed February 16, 1897. Serial No. 623,644. (No model.)

To all whom it may concern:

Be it known that we, HARRY M. NEWKIRK and HENRY A. SCHMIDT, residing at Newport News, in the county of Warwick and State of Virginia, have invented a new and useful Crank Connection for Steam-Engines, of which the following is a specification.

This invention relates generally to an improvement in steam-engines, and more particularly to that class known as "stationary" engines. The same especially relates to mechanical arrangements for converting the reciprocating motion of the piston into the rotary motion of the drive-shaft.

One of the principal objects of our invention is to avoid the lost motion so common in this class of engines and also to prevent the sudden jerk or jar which is found so detrimental to the general construction of engines of this class now in use.

With these various objects in view our invention consists, essentially, in a reciprocating rectangular frame having the rack-teeth upon the opposite sides thereof arranged in a definite manner with regard to the length of the frame, so that the rack-bar upon the opposite side of the frame will alternately engage the teeth of the mutilated gear which is connected to the power-shaft, so that the power-shaft is continually driven in a defined direction in combination with a connection between the mutilated gear and sliding frame, whereby the gear and frame are always held in positive engagement with each other, thereby preventing any danger of lost motion between the same.

In the drawings forming a part of this specification, Figure 1 represents a perspective view showing our invention in use. Fig. 2 is a view, partly in section, showing the rack-bars and the engine proper in side elevation. Fig. 3 is a detail plan view. Fig. 4 is a vertical cross-section taken on the line 4-4 of Fig. 2. Fig. 5 is a detail view showing the cylinder-head detached.

In carrying out our invention we employ any desired construction of cylinder and steam-chest A for operating the piston-rod B, which works through the end piece of the supporting-frame D, said supporting-frame being suitably mounted at the desired dis-

tance from the engine-cylinder, and sliding in said supporting-frame is a rectangular-shaped frame E rigidly connected with the forward end of the piston-rod, as most clearly shown in the drawings, said rectangular-shaped frame E, having a rib E', which is adapted to enter a V-shaped groove D', formed in the faces of the supporting-frame D, this construction insuring the steadiness of the reciprocating frame within the supporting-frame.

The rectangular-shaped reciprocating frame E has the internal rack-bars F and F', the rack-bar F' being arranged slightly offset longitudinally in relation to the rack-bar F, said bars being adapted to alternately mesh or engage the teeth of the pinion G, said pinion being mounted upon a drive-shaft H, which is generally journaled and provided with a fly-wheel H'.

The pitman E² is pivotally connected to the end of the reciprocating frame and is connected with the mutilated gear at a point adjacent to the circumference of the said gear, the purpose of said pitman and connection being to insure the positive engagement of the mutilated gear and the rack-bars, so as to avoid all lost motion.

The stud or pin L, carried by the crank-disk and the pitman E², is for the purpose of keeping the sliding rack F and the pinion G in their proper positions. The crank on the end of the pin L is adjustable and is made stationary by suitable set-screws H. This crank is employed in place of an eccentric, which is usually employed on the ordinary form of steam-engines. The said crank is connected to the valve-rod C.

It will thus be seen that we provide an exceedingly cheap and simple construction of engine attachment whereby the reciprocating motion of the piston-rod is transferred and a steady and even rotary motion of the power-shaft is produced. Lost motion is thereby avoided, obviating the jerk or jar so common among engines now in use.

Various slight changes might be made in the forms and construction of the parts herein described without departing from the spirit and scope of our invention. Hence we do not wish to limit ourselves to the exact construc-

tion herein set forth, but consider ourselves entitled to all such changes as fall within the spirit and scope of our invention.

Having thus described our invention, what we claim as new, and desire to secure by Letters Patent, is—

1. The combination with the reciprocating frame, having internal rack-bars, the mutilated gear arranged within the frame and adapted for engagement with the rack-bars, and a pitman connected to one end of the reciprocating frame and eccentrically attached to the mutilated gear, substantially as shown and described.
2. The combination with the reciprocating frame having internal rack-bars, one arranged in advance of the other, of the mutilated gear adapted for engagement with the rack-bars, and the pitman connected to one end of the reciprocating frame and eccentrically connected to the mutilated gear, substantially as shown and described.
3. The combination with the supporting-frame, of the reciprocating frame working therein, said reciprocating frame having rack-bars, the mutilated gear and the pitman connecting the mutilated gear and reciprocating frame, substantially as shown and described.
4. The combination with the supporting-frame having the V-shaped grooves upon the

inner faces, of the reciprocating frame having double-edged ribs adapted to engage the grooves of the supporting-frame, the internal rack-bars carried by the reciprocating frame, the mutilated gear adapted for engagement with the rack-bars, and the pitman connecting the mutilated gear and the end of the reciprocating frame, substantially as shown and described.

5. In an engine, the combination with the cylinder, piston and piston-rod, of the supporting-frame having the V-shaped grooves upon the inner faces, the reciprocating frame having the double-edged exterior ribs and the internal rack-bars, the mutilated gear arranged within the frame and adapted for engagement with the rack-bars, the pitman connecting the end of the frame with the mutilated gear at a point beyond the center and adjacent to the teeth, the shaft H, and balance-wheel H', the crank-disk M, the shaft N, and the band-wheel N', all arranged and adapted to operate, substantially as shown and described.
